US00D949295S

(12) **United States Design Patent** (10) **Patent No.:** **US D949,295 S**
(45) **Date of Patent:** **** Apr. 19, 2022**

(54) **CONNECTOR FOR A SANITIZING MACHINE**

(71) Applicant: **SoClean, Inc.**, Peterborough, NH (US)
(72) Inventor: **Alex Chaves**, Hudson, NH (US)
(73) Assignee: **SOCLEAN INC.**, Peterborough, NH (US)

(**) Term: **15 Years**

(21) Appl. No.: **29/725,728**

(22) Filed: **Feb. 26, 2020**

(51) LOC (13) Cl. **23-01**
(52) U.S. Cl.

USPC **D23/262; D24/129**

(57) **CLAIM**

The ornamental design for a connector for a sanitizing machine connector, as shown and described.

DESCRIPTION

FIG. 1 is a front view of a connector for a sanitizing machine, showing the new design;
FIG. 2 is a rear view thereof;
FIG. 3 is a left side view thereof;
FIG. 4 is a right side view thereof;
FIG. 5 is a bottom view thereof;
FIG. 6 is a top view thereof;
FIG. 7 is a front top perspective view thereof;
FIG. 8 is a front bottom perspective view thereof;
FIG. 9 is a front left top perspective view thereof;
FIG. 10 is a front right top perspective view thereof;
FIG. 11 is a front right bottom perspective view thereof;
FIG. 12 is a front left bottom perspective view thereof;
FIG. 13 is a right side top perspective view thereof;
FIG. 14 is a right side bottom perspective view thereof;
FIG. 15 is a rear top perspective view thereof;
FIG. 16 is a rear top right perspective view thereof;
FIG. 17 is a rear top left perspective view thereof;
FIG. 18 is a rear bottom perspective view thereof;
FIG. 19 is a rear bottom left perspective view thereof; and,
FIG. 20 is a rear bottom right perspective view thereof.
The broken lines in the figures show portions of the connector for a sanitizing machine that form no part of the claimed design.
